[57] CLAIM

The ornamental design for an antenna mounting bracket, substantially as shown and described.

DESCRIPTION

FIG. 1 is a side elevation view of an antenna mounting bracket including my new design.

FIG. 2 is a view in elevation of the antenna mounting bracket illustrated in FIG. 1 as it appears when viewed from a side displaced 90° from the side shown in FIG. 1. FIG. 3 is an elevation view of the opposite side of the antenna mounting bracket from that which is shown in FIG. 2.

FIG. 4 is a top plan view of the antenna mounting bracket shown in FIG. 1.

FIG. 5 is a bottom plan view of the antenna mounting bracket shown in FIG. 4.
